Primary Examiner — R. Johnson(74) *Attorney, Agent, or Firm* — Morland C. Fischer(57) **CLAIM**

The ornamental design for a back and seat for a chair, as shown and described.

DESCRIPTION

FIG. 1 is a top, right, front perspective view of a back and seat for a chair showing my new design;

FIG. 2 is a top, left, rear perspective view thereof;

FIG. 3 is a front elevational view thereof;

FIG. 4 is a right side devotional view thereof;

FIG. 5 is a rear elevational view thereof;

FIG. 6 is a left side elevational view thereof;

FIG. 7 is a top plan view thereof; and,

FIG. 8 is a bottom plan view thereof.

The long broken lines in the figures indicate environment that forms no part of the claimed design. The shorter broken lines in the figures represent stitching.
